(57) **CLAIM**

The ornamental design for a watch bracelet as shown and described.

DESCRIPTION

1. Watch bracelet

1.1 Perspective

1.2 Front

1.3 Back

1.4 Top

1.5 Bottom

1.6 Left

1.7 Right

1.8 Partial enlarged view of the area 1.8 shown in image 1.1

1.9 Partial enlarged view of the area 1.9 shown in image 1.2

1.10 Partial enlarged view of the area 1.10 shown in image 1.3

The watch bracelet as shown in images 1.1-1.3 includes oval features. The interior of all oval features is disclaimed. The enlarged views of images 1.8-1.10 show broken line boundary lines within the interior of the oval features. All oval features in images 1.1-1.3 include these broken line boundary lines. The broken line boundary lines and the area within the broken line boundary lines, are disclaimed and form no part of the claimed invention.

1 Claim, 10 Drawing Sheets
